US0D1021510S

(12) **United States Design Patent** (10) **Patent No.:** **US D1,021,510 S**
(45) **Date of Patent:** **** Apr. 9, 2024**

(54) **COOKING APPLIANCE**

(71) Applicant: **WHIRLPOOL CORPORATION**,
Benton Harbor, MI (US)

(72) Inventors: **XinFeng Huang**, Shenzhen (CN); **Yu Liu**, St. Joseph, MI (US); **Kyle A. Walters**, Benton Harbor, MI (US); **XunCai Zhang**, Shenzhen (CN); **Bin Huang**, Shenzhen (CN)

(73) Assignee: **WHIRLPOOL CORPORATION**,
Benton Harbor, MI (US)

(**) Term: **15 Years**

(21) Appl. No.: **29/817,406**

(22) Filed: **Dec. 1, 2021**

Related U.S. Application Data

(63) Continuation of application No. 29/695,598, filed on Jun. 20, 2019, now Pat. No. Des. 939,884.

(51) **LOC (14) Cl.** **07-02**

(52) **U.S. Cl.** **USPC .....** **D7/349**

(57) **CLAIM**

The ornamental design for a cooking appliance, as shown and described.

DESCRIPTION

FIG. 1 is a perspective view of a cooking appliance according to the design;

FIG. 2 is a front view thereof;

FIG. 3 is a back view thereof;

FIG. 4 is a right view thereof;

FIG. 5 is a left view thereof;

FIG. 6 is a top view thereof; and,

FIG. 7 is a bottom view thereof.

The portions of the cooking appliance shown in even broken line form no part of the claimed design.

Dash-dot-dot-dash broken lines show environment only and form no part of the claimed design.

1 Claim, 7 Drawing Sheets
